UNITED STATES PATENT OFFICE.

ERNEST E. LICKISS, OF OAKLAND, CALIFORNIA, ASSIGNOR OF ONE-THIRD TO ROBERT KING AND ONE-THIRD TO JOHN B. SPANGLER, BOTH OF OAKLAND, CALIFORNIA.

OPERATING MEANS FOR WASHING APPARATUS.

1,379,830.

Specification of Letters Patent. Patented May 31, 1921.

Original application filed January 5, 1920, Serial No. 349,489. Divided and this application filed September 7, 1920. Serial No. 408,530.

To all whom it may concern:

Be it known that I, ERNEST E. LICKISS, a citizen of the United States, residing at Oakland, in the county of Alameda and State of California, have invented certain new and useful Improvements in Operating Means for Washing Apparatus, of which the following is a specification.

The present invention is a division of application Serial No. 349,489, filed January 5, 1920, and relates to what may be termed a permanent laundry installation wherein a washing container is mounted in a permanent tub installation and wherein there is associated with the permanent tub mounting the container, other tubs, either one or two in number, for receiving the laundried articles as removed from the washing container tub, either for rinsing or bluing.

The present invention has for its principal objects to provide a permanent laundry installation wherein a plurality of tubs are provided and are permanently associated together, and one of said tubs mounting a washing container. A further object is to provide a novel means for operating said container, whereby the same is rotated in one direction for a given number of revolutions; is thence permitted to come to a point of rest, and is then rotated in a reverse direction, thus alternate rotation and intervals of rest being performed in successive cycles. A further object is to provide in connection with said tubs a wringer permanently associated with the tubs and adapted for positioning in coöperative relation between either of the tubs, and to incorporate in connection with said wringer a means common to all of the tubs for operating the wringer.

With the above mentioned and other objects in view, the invention consists in the novel construction and combination of parts hereinafter described, illustrated in the accompanying drawings and pointed out in the claims hereto appended; it being understood that various changes in the form, proportion, size and minor details of construction within the scope of the claims may be resorted to without departing from the spirit or sacrificing any of the advantages of the invention.

To more fully comprehend the invention,

reference is directed to the accompanying drawings, wherein—

Figure 1 is a view in broken side elevation, disclosing the preferred embodiment of my invention, and illustrating the wringer in dotted lines as being positioned between the auxiliary tubs.

Fig. 2 is a vertical sectional view of the washing cylinder operating means taken on line 2—2 of Fig. 1.

Fig. 3 is a transverse sectional view of the washing cylinder operating means taken on line 3—3 of Fig. 2.

Fig. 4 is a central vertical sectional view taken on line 4—4 of Fig. 2.

Fig. 5 is a transverse sectional view taken on line 5—5 of Fig. 2.

Referring more particularly to the drawings, wherein like characters of reference designate corresponding parts—1 indicates a suitable washing tub having permanently associated therewith the auxiliary tubs 2 and 3, said tubs being preferably of the commonly known enamel or soap-stone construction, and having open tops 4, and supported in any suitable manner, as by the legs 5. Associated with the tubs 1 and 2 are the permanent drain outlets 6, the outlet of the tub 1 being controlled by a stopper 7 adapted to be moved to and from operative position by a rod 8 connected therewith and extending through guides to the open top of said tub, as illustrated in Fig. 1.

Within opposite ends of the tub 1 are positioned suitable alined bearings 9 in which are received the stub shafts 10 and 10' positioned at the opposite ends of a suitable cylinder 11 positioned within the tub 1 and rotatable therein.

Extending through the end wall of the tub 1 and having driving connection with the stub shaft 10' is a suitable driven shaft 95 12 which extends into and rotates within a casing 13 secured to the outer surface of the end wall of the tub, as illustrated in Figs. 1 and 4 of the drawings. The driven shaft 12 is preferably horizontally disposed, and 100 extending vertically into said casing 13 is a drive or power shaft 14, the lower end of which is driven by any suitable mechanism, preferably an electric motor 15, illustrated as being secured to one of the supporting legs 5. The drive shaft 14 extends

2
preferably vertically through one corner of the casing 13, as illustrated in Fig. 3 of the drawings, and carries a pinion gear 16 which intermeshes with an intermediate gear 17 rotatably mounted on a shaft 18 extending upwardly from the bottom wall of the casing 13. The gear 17 in turn engages a pinion gear 19 on the lower end of a vertically disposed countershaft 20 rotatably mounted in bearings 21 preferably diagonally disposed within the casing 13 from said shaft 14.

By referring to Fig. 5 of the drawings it will be observed that the rotating of the shaft 14 in the direction of the arrow imparts a corresponding rotation to the countershaft 20. The drive shaft 14 and countershaft 20 carry respectively the worm pinions 22 and 23, mounted to rotate therewith, preferably in a plane parallel with the driven shaft 12. Loosely mounted on opposite ends of the shaft 12, within the casing 13, are the spiral gears 24 and 25 which coöperate respectively with the worm pinions 22 and 23, and the adjacent faces of the hubs of said spiral gears 24 and 25 are provided with the respective clutch faces 26 and 27 disposed in opposite directions, as illustrated in Fig. 3 of the drawings.

30 The adjacent faces of the hubs of the respective worm-gears 24 and 25 normally lie in spaced relation, as in Figs. 3 and 4 of the drawings, and between said adjacent hub faces is positioned a clutch dog member 28 capable of sliding movement longitudinally of the shaft 12 on a key 29, which causes said clutch dog to rotate with the shaft 12. The clutch dog or member 28 is provided, preferably in its center, with an annular groove 29', and at one end is provided with a clutch surface 30 for engaging the clutch face 26 of the hub of the spiral gear 24, and at its opposite end is provided with a clutch face 31 for engagement with the clutch face 27 of the hub of the spiral gear 25, this construction being particularly illustrated in Fig. 3 of the drawings.

It will be apparent that the direction of rotation of the driven shaft 12 depends on the position of the clutch dog 28 longitudinally of the shaft 12, and that when the same lies in the position, indicated in Fig. 3, the shaft 12 will be driven in the direction indicated by the arrow associated with the shaft 12, in Fig. 3, and when said clutch dog lies intermediate the hubs of the spiral gears 24 and 25, no driving connection is had from either of said spiral gears to the shaft. Therefore, no rotation is imparted to the shaft, and on the other hand, when the clutch dog is moved to a position reverse to that illustrated in Fig. 3, the shaft 12 is driven in a direction corresponding to the arrow on the hub of the spiral gear 24.

65 To reciprocate the clutch dog 28 longitudi-

dinally of the shaft 12 to rotate the shaft alternately in opposite directions, and to provide a point of rest between said rotative movements, I prefer to employ the following mechanism.

70

Disposed parallel with the shaft 12, preferably above the same, is a suitable auxiliary shaft 32 extending transversely of the casing 13 and rotatably mounted at its ends in bearings 33 in the end walls of the casing.

75

Keyed to rotate with the shaft 32 is a star wheel 34 the periphery of which is disposed adjacent the inner periphery of the spiral gear 24. Extending laterally from the inner face of the spiral gear 24 is a suitable pin 35 which is adapted, on each complete revolution of the spiral gear 24, either on the shaft 12 or with the shaft 12, to engage one of the teeth of the star wheel 34 and rotate the same a partial revolution, which in turn rotates the shaft 32 a partial revolution. The star wheel 34 in its hub is provided with an annular groove 36 with which coöperates a pin 37 on the inner end of a lever 38, the outer end of which projects through an opening 39 in the casing 13. The lever is fulcrumed within its length at a point 40 and said lever provides a manual means for sliding said star wheel 34 longitudinally of the shaft 32 to move the teeth thereof outside the path of the pin 35, which permits the shaft 12 to remain at a point of rest at such time as the clutch dog 28 lies in a position with its clutch faces disengaged from the clutch faces of the respective worm gears 24 and 25.

95

To provide an automatic movement of the clutch dog 28 between the clutch faces of the spiral gears 24 and 25 to cause an alternate rotation of the shaft 12 in opposite directions, I mount on the auxiliary shaft 32 a member 41 having a cam groove 42 in which is received a pin 43 upwardly projecting from a pivotally mounted lever 44, the free end of which carries a pin 45 extending into the groove 29' of the clutch dog 28. The rotation of the shaft 32 through the cam groove 42 causes a swinging movement of the free end of the lever 44, which in turn transmits a reciprocating movement to the clutch dog 28 longitudinally of the shaft 12, positioning the same alternately in engagement with the clutch faces of the respective worm gears 24 and 25. During its movement between said clutch faces, power is not transmitted to the shaft 12, permitting said shaft to come to a point of rest between its reverse directions of rotation.

105

110 It will be apparent that a number of revolutions of the spiral gear 24 is required to make a complete revolution of the star wheel 34, and thus make a complete reciprocating movement of the clutch dog 28 longitudinally of the shaft 12.

125

130

The drive shaft 14 projects upwardly through the casing 13, and at a point approximately level with the upper end of the tub 1 has geared connection within a casing 46 with a shaft 47 extending longitudinally of the tubs 1, 2 and 3. The shaft 47 is adapted to impart operative movement to any suitable form of wringer or expressing mechanism 48 which is capable of longitudinal movement on the shaft 47 from the position indicated in full lines—Fig. 1 to that indicated in dotted lines—Fig. 1, whereby said expressing mechanism is capable of positioning between the tubs 1 and 15 2 or between the tubs 2 and 3.

Having thus described my invention what I claim is:

1. A driving device for washing apparatus including, a shaft, a pair of gears 20 loosely mounted on said shaft in spaced relation, means for rotating said gears in opposite directions, means associated with said shaft between said gears to alternately clutch said gears in engagement with said 25 shaft to cause said shaft to be rotated alternately in opposite directions, a cam associated with said clutch, means for operating the same, a star wheel associated with said cam, and a pin associated with one of said 30 gears for operating said star wheel to cause a rotation of said cam to operate said clutch.

2. A driving device for washing apparatus including a shaft, a pair of gears loosely mounted on said shaft in spaced relation, means for rotating said gears in opposite directions, means associated with said shaft between said gears to alternately clutch said gears in engagement with said shaft to cause said shaft to be rotated alternately in opposite directions, a cam associated with said clutch means for operating the same, a star wheel associated with said cam, a pin associated with one of said gears for operating said star wheel to cause a rotation of said cam to operate said clutch, and a lever associated with said star wheel for moving the same outside the path of said pin.

3. A driving device for washing apparatus including a driven shaft, a pair of worm wheels loosely mounted thereon, a pair of driving worms, one for each worm wheel, said worms being in mesh with opposite sides of said worm wheels, means for driving the worms continuously in one direction, a clutch splined to the driven shaft between the worm wheels for engaging the same one at a time, and means for automatically moving the clutch into alternate engagement with the respective worm 55 wheels.

4. A driving device for washing apparatus including a horizontal driven shaft, a pair of worm wheels loosely mounted thereon, a pair of vertical shafts, a worm on each shaft, one co-operating with each worm wheel, an intergeared connection between said pair of vertical shafts whereby said shafts are caused to rotate in the same direction, a clutch member splined to the 65 driven shaft between the worm wheels for engaging the respective worm wheels one at a time, and means associated with the clutch for automatically shifting the same for reversing the direction of rotation of said 70 driven shaft.

5. A driving device for washing apparatus including a shaft, a pair of worm gears each loosely mounted on the shaft, a pair of intergeared worms, one engaging 80 each worm gear for driving said gears in reverse directions, a clutch splined to said shaft between the gears and engageable alternately with said gears, a second shaft, a star wheel thereon, a clutch shifting lever, 85 an operating connection between the second shaft and the lever, and a pin on one of said gears for engaging said star wheel for operating the clutch shifting lever to move said clutch into engagement with one of 90 said gears and from engagement with the other.

In testimony whereof I have signed my name to this specification.

ERNEST E. LICKISS.
